UNITED STATES PATENT OFFICE.

BYRD C. ROCKWELL, OF CAMDEN, ARKANSAS.

TEMPLATE STRIP.

Application filed August 27, 1921. Serial No. 496,152.

To all whom it may concern:

Be it known that I, BYRD C. ROCKWELL, a citizen of the United States, residing at Camden, county of Ouachita, and State of Arkansas, have invented a certain new and useful Improvement in Template Strips, of which the following is a full, clear, and exact description, such as will enable others skilled in the art to which it appertains to make and use the same, reference being had to the accompanying drawings, forming part of this application.

This invention relates to a template strip or bar for spacing door hinges and the like, and the objects of the invention are to provide a simple and efficient means designed to be used to properly space and hold in their respective positions hinge members while the same are being secured in position.

Still further objects of my invention are to provide a spacing bar of the class described, which can be easily applied and is inexpensive to manufacture, and can be easily broken and quickly removed after the hinge members have been secured in position.

With the foregoing and other objects in view, my invention consists in certain novel features of construction and arrangement of parts, hereinafter more fully described and claimed, and illustrated in the accompanying drawings, in which—

Figure 1 is a front elevation of a door casing with the template strip applied thereto.

Figure 2 is a front elevation of the door casing after the template strip has been removed and a door placed in position.

Figure 3 is a horizontal cross section taken on the line 3—3 of Figure 1.

Figure 4 is a horizontal cross section taken on the line 4—4 of Figure 2.

Figure 5 is a detail perspective view of the template strip partly broken away with some of the hinge members in position.

Referring by numerals to the accompanying drawings, 10 indicates a door casing on which is hinged a screen door 11 which is designed to engage the outside of said casing. The hinges consist of screw-eyes 14 secured to casing 10 at the proper points and hook members 15 fixed to and projecting from the edge of the stile of door 11. The stiles of each door are bored at the factory to receive and accurately space hooks 15.

In order to locate screw eyes 14 which form bearings for hooks 15 and support door

11 in position on casing 10 at the exact points on said casing so that they will register with hooks 15 and support door 11 in proper position, I provide a template strip 60 or spacing bar 17 which is preferably rectangular in cross section and of a length equal to the height of said door. Centrally disposed in said strip and equidistant from both ends thereof and from each other are 65 transverse apertures 18 which are designed to temporarily receive the shanks 14^a of screw eyes 14.

In placing the screw eyes 14 in position on the casing, strip 17, with said screw eyes 70 occupying apertures 18, is placed on the jamb of the casing 10 flush with the inner side of said jamb, said template strip being of the proper width so that hinge members positioned in apertures 18 are spaced the 75 desired distance from the inner side of said jamb. The hinge members are then secured in position on the casing, the thickness of the template strip 17 being used as a guide in driving said hinge members into casing 80 10. Thus the template strip is used to locate the hinge members the proper distance from the inner edge of the jamb and seating the hinge members the desired distance in said door casing so that the cooperating hinge 85 members carried by the door will register with the hinge members secured to the casing and the proper clearance will be provided for accurately positioning door 11 on casing 10. 90

The template strip 17 is provided along its edges with saw kerfs 19 which terminate in apertures 18. When the hinge members 14 or 15, as the case may be, are secured to the door casing, said template can be easily 95 broken away at points where said kerfs 19 are formed, without affecting said hinge members.

In practice, I prefer to stagger the saw kerfs 19 by alternately arranging the saw 100 kerfs on both edges of the strip.

By the aid of my template strip, a door or other hinged closure member can be accurately and readily placed in position at a great saving of time and labor and without 105 the use of special tools.

A template strip made according to my invention is inexpensive so that it can be furnished with every door by the manufacturer, and being of simple construction 110 can be easily applied by an inexperienced person.

While I have shown and described screw eyes 14 as the casing hinge members, if desired, hooks 15 may be used as the casing hinge members and screw eyes 14 as the door hinge members, or hinges of any other construction may be used.

I claim:

1. A template strip for positioning hinge members, said strip being provided with a plurality of apertures for temporarily receiving said hinge members and having saw kerfs formed in its edge adjacent to each aperture whereby said strip may be broken in sections and removed after the hinges are in position.
- 10 2. A template strip for positioning hinge members, said strip being provided with a plurality of recesses spaced equidistantly from each other and from the ends of said strip and adapted to temporarily receive said hinge members, said strip being provided in its edge with notches whereby the strip may be broken into sections after the hinges are secured in position.
- 15 3. A template strip for positioning hinge members, said strip being provided with a plurality of recesses spaced equidistantly from the edges and ends thereof and adapted to temporarily receive said hinge members, said strip being adapted to be broken in sections to facilitate its removal after the hinges are secured in position.
- 20 4. A template strip which is rectangular

in cross section and of a predetermined length and is provided with a longitudinally disposed series of transverse apertures which are designed to be occupied by hinge members before they are secured to their respective positions on the closure casing, said strip being adapted to be broken in sections to facilitate its removal after the hinges are secured in position.

5. A template strip rectangular in cross section and having a longitudinally disposed series of apertures arranged to receive and space hinge members on the closure casing in register with the hinge members on the closure member, there being saw kerfs formed in the edge of said template strip whereby the same can be easily broken in sections and removed when said hinge members are permanently secured in position on the casing.

6. A spacing bar for hinge members for doors and the like, said bar being perforated at spaced intervals to receive and hold the stationary members of a hinge in their respective positions, there being saw kerfs formed in said bar whereby it can be broken into sections to facilitate its removal after said hinge members are secured in their permanent positions.

In testimony whereof I hereunto affix my signature this 17th day of August, 1921.

BYRD C. ROCKWELL.
